NELSON STAFFORD, OF BROOKLYN, NEW YORK.

Design No. 4,427, dated October 18, 1870.

DESIGN FOR A KEY-RING TAG.

The Schedule referred to in these Letters Patent and making part of the same

To all whom it may concern:

Be it known that I, NELSON STAFFORD, of Brooklyn, in the county of Kings and State of New York, have invented and produced a new and original Design for Tags for Keys, Checks, &c.; and the following is hereby declared to be a correct description thereof.

In the annexed drawings I have represented an elevation of my said tag.

a represents the medallion portion, and upon the same is represented the picture of the "seven boys," and the said illustration of the "seven boys" is to be stamped or otherwise produced upon the tag.

b represents the tablet or name portion of the tag,

the same being formed with a blank space to allow of a name or device being stamped or marked thereon.

The edge of the tablet portion is ornamented with scroll-work, as at *c*.

At *d* an opening is provided to allow of the tag being connected to a key-ring or other article.

I claim as my invention—

The design of the tag, substantially as represented. Signed by me this 19th day of September, 1870.

N. STAFFORD.
